UNITED STATES PATENT OFFICE.

HOWARD T. HALLOWELL, OF PHILADELPHIA, PENNSYLVANIA.

METAL BENCH-LEG.

1,379,623.

Specification of Letters Patent. Patented May 31, 1921.

Application filed August 9, 1919. Serial No. 316,357.

To all whom it may concern:

Be it known that I, HOWARD T. HALLOWELL, a citizen of the United States, residing in Philadelphia, Pennsylvania, have invented certain Improvements in Metal Bench Legs, of which the following is a specification.

My invention relates to metal benches, metal bench legs, or supports for work 10 benches, tables and the like, and the object of my invention is to provide an improved structure in which the legs may be formed of sheet or structural metal, pressed or otherwise formed into shape; said legs being combined with suitable bracket members and connecting elements whereby a rigid self-sustaining frame is provided, much lighter than the cast structures heretofore employed and readily assembled from 15 parts pressed or otherwise formed into suitable shape. As may be readily understood, I may employ with any pressed metal parts, parts of any usual or commercial structural shape which may also be reshaped in any 20 portion thereof as may be desired to produce structures within the scope of my invention, and some cast parts.

These and other features of my invention are more fully described hereinafter, 30 reference being had to the accompanying drawings, in which:

Figure 1, is an elevation of a bench leg or work table support within the scope of my invention.

Fig. 2, is a sectional view on the line 35 II-II, Fig. 1, illustrating the connection of the leg with one of the supports for the table portion of the bench structure.

Fig. 3, is a similar sectional view illustrating a modified construction within the scope of my invention.

Fig. 4, is a plan view, partly in section on line IV-IV, Fig. 1.

Fig. 5, is a sectional view on the line 45 V-V, Fig. 4.

Fig. 6, is a sectional plan view on the line VI-VI, Fig. 1.

Fig. 7, is a sectional view on the line VII-VII, Fig. 6.

50 Figs. 8 and 9, are sectional views illustrating other forms of legs and braces for use with structures of the type shown in Fig. 1, within the scope of my invention.

Fig. 10, is a sectional view on the line 55 X-X, Fig. 8.

Fig. 11, is a sectional view on the line XI-XI, Fig. 9.

Fig. 12, is a view similar to Fig. 1, illustrating another form of bench leg or work 60 table support within the scope of my invention.

Fig. 13, is a plan view of a portion of the same illustrating a detail of my invention.

Fig. 14, is a sectional view on the line 65 XIV-XIV, Fig. 12.

Fig. 15, is a sectional view on a slightly larger scale, illustrating a modified construction within the scope of my invention.

Fig. 16, is a view similar to Figs. 1 and 12, illustrating another form of bench leg 70 or work table support within the scope of my invention.

Fig. 17, is a perspective view illustrating a form of cross bar connection for the type of structure shown in Fig. 16.

Fig. 18, is a view similar to Fig. 1, of another form of bench leg or work table support within the scope of my invention.

Fig. 19, is a front elevation of one of the legs shown in Fig. 18.

Fig. 20, is a sectional view on the line 80 XX-XX, Fig. 18.

Fig. 21, is a view of a portion of the top of a bench structure within the scope of my invention.

Fig. 22, is a similar view illustrating another form of structure.

Fig. 23, is a perspective view of a detail of the structure shown in Fig. 22.

Fig. 24, is a sectional view on the line 90 XXIV-XXIV, Fig. 22.

Fig. 25, is a sectional view on the line XXV-XXV, Fig. 22.

In Fig. 1, of the drawings, 1, 1, represent legs of the bench support which may be 95 made of pressed-up metal in substantially straight angular shapes, commercial channel shapes, or the like, performed in any suitable manner, and which may have a cross section in a horizontal plane such as illustrated in Figs. 4 and 6, or the cross sections illustrated in Figs. 8 and 9. In Figs. 4 and 6, these legs are shown as of channel-shape, having a web 1^a, and side flanges 1^b. The form of leg shown in Figs. 8 and 10, has its 105 side walls provided with inturned reinforcing or strengthening flanges 1^c, while the form shown in Figs. 9 and 11 has, in addition to the inturned flanges 1^c, outturned flanges 1^d.

The upper ends of the legs may be notched at 3 for the reception of the depending flanges 4 of angle members 5 forming horizontal supporting means for the table 6 of the bench, and spacing and connecting said legs. At the rear of the bench, brackets 7 may be provided, against which the back 8 of the bench may rest. The upper ends of the legs 1 may be riveted, bolted, or welded 10 to the angle members 5 as at 9, and the brackets 7 may be riveted or otherwise secured to said angle members as at 10.

In the connection shown in Fig. 3, the upper end of the leg may be split at 3 in the same manner as illustrated in Fig. 2, but instead of employing a pair of angle members such as shown at 5, a single angle member 5^a, T-shape in cross-section, may be employed; the flange 4^a of the same being 20 secured to the leg 1 by bolts, rivets, or the like, as indicated at 9^a.

In connecting these legs to the angle members, whether by riveting or bolting, filling pieces 11 are preferably interposed 25 between the side walls 1^b of said legs and the depending flanges or flange of the angle members employed. The upper ends of the side walls 1^b of the legs are preferably turned over at 12 and lie beneath the horizontal flanges of the angle members 5 or 5^a, 30 as clearly shown in Figs. 2 and 3.

In the form of leg shown in Fig. 1, cross braces 15 of metal, preferably U-shape in cross section, may be employed, which may 35 be riveted or bolted to the side walls 1^b of the leg 1 or to other convenient portions thereof, as shown at 16, Figs. 1, 4 and 5. When the leg is of the shape shown in Figs. 4 and 5, the cross braces may be attached 40 directly to the side walls 1^b of the same. When the leg is of the type shown in Figs. 8 and 10, the cross braces 15^a may be narrower, and may be connected to the lateral flanges 1^c of the leg, instead of to the side 45 walls 1^b of the same, as indicated at 16^a. In the same way, braces 15^b of substantially the same dimensions will be employed with 50 the form of leg illustrated in Figs. 9 and 11, and this form of brace may have a turned-down end 17 to be secured to the rear wall of the leg by a rivet 16^b, and filler pieces 18 may be interposed between the side walls of the cross brace and the sides 1^b of the leg through which securing bolts or rivets 19 55 may pass.

The cross braces preferably carry a board or series of boards 20 to form a shelf for the bench, which may be provided with a back 21; such boards being suitably secured 60 to the legs and cross braces in any suitable or approved manner. Additional cross braces may be provided, if desired and, if employed, they may form supports for other shelves with which the bench structure may 65 be equipped.

The form of feet which I may employ with these legs is more clearly illustrated in the sectional plan view and elevation, Figs. 6 and 7, in which 22 represents a pressed-up member having a top 23 and side 70 portions 24, which latter portions may be secured to the lower ends of the legs by bolts or rivets 25; the top having a flange 26 bent up from the same which may be secured to the leg by a rivet or bolt 27. To give 75 ample support to the securing means, I may provide a substantially U-shape filler piece 28 within the foot, having turned ends 29 which may be secured to the web 1^a of the leg by rivets or bolts 30. The top of the 80 foot is apertured at 31 for the reception of the usual bolt 32 whereby the leg structure may be secured to the floor, and such bolt passes down between the walls of the U- 85 shape filled piece 28.

Other forms of bench leg supports are within the scope of my invention, and in Fig. 12, I have shown legs 1^d made of structural or angular metal which may be V-shape in cross section, and in which the upper end is slit or split at 35 to receive the depending flanges of the angle members 4, while the lower end is flared and flanged to form a foot which is preferably struck up as at 36 to stiffen the same. The upper ends 95 of the side walls of the leg have portions 37 to underlie the horizontal portions of the angle members 4, to which they may be secured by rivets 39. A cross section of this form of leg is shown in Fig. 14, which also 100 illustrates a cross brace 15^c for legs of this type, having depending ends 40 which may be secured to the leg by means of rivets 41.

In the structure shown in Fig. 1, the bench structure is provided with brackets 7, 105 against which the back 8 rests; such back serving as a stiffening member for a plurality of the bench leg structures.

In Fig. 12, I have shown a back member 8^a which serves as a stiffening member, to 110 which brackets 7^a may be attached; the securing means being in the form of bolts 42 which pass through the leg, the back 8^a, and the flanges of the bracket 7^a.

In Fig. 16, I have shown a structure in 115 which the legs 1^d have a cross section of the character illustrated in Fig. 17, being of shaped metal with their lower ends flared and flanged to form a foot of substantially the same character as the structure illustrated in Fig. 12, while portions of the flanges at the upper ends are turned out, as 120 illustrated at 37^a, to underlie the horizontal portions of the angle members 4, to which they may be secured by rivets 39^a. In this 125 form of structure, the cross brace may be in the form illustrated at 15^d, substantially channel-shaped, as shown in Fig. 17, having outturned ends 43 secured to the flanges of the legs by rivets 44; such outturned ends 130

being additionally retained by the beaded edges 45 of the leg. If desired, a covering member 46 may be employed on top of the channel member 15^a; the latter having out-turned flanges 47 around which the edges of the plate 46 are folded. In this form of structure, I have illustrated a longitudinal bracing element 8^b, which may be secured to the legs by bolts 42^a; such bracing member being suitably cut out to accommodate the vertical flanges of the angle members 4. When a leg of this type is employed, I may also provide the same with a bracket construction such as illustrated in Fig. 15, wherein I have shown angle members 48 lying between the walls of the rib of the leg and the angle members 4, being secured in place by rivets 49. These angle members in turn may be riveted to a back member 8^c by bolts 50, while the bracket member 7^c is also secured to the structure by said bolts. In Fig. 18, I have shown another form of structure in which legs of substantially the same type as those illustrated in Fig. 16, 25 may be employed. In this instance, the upper ends of the leg are split and flared out, as clearly shown at 51 in the end elevation, Fig. 19, and the sectional view, Fig. 20, and additionally the angle members 4 are depressed at the points 52, providing portions which engage the expanded or flared portions of the legs, and are secured thereto by rivets 53, as clearly shown in Fig. 20. In this type of structure, I have employed a 30 bracing member 8^b, of substantially the character illustrated in Fig. 16; the same being secured by bolts 42^a. The cross brace 15^a may be exactly the same type as that illustrated in Fig. 16.

In Figs. 21 and 22, I have shown legs 1^c which are channel-shape, as clearly illustrated in the sectional views, Figs. 24 and 25, and to which the angle members 4^a are secured. In the form of structure shown in Fig. 21, I take an angle member and cut the vertical flanges to V-shape, and then bend down the back piece 4^b, and join the flanges by welding, in any suitable manner, at the line x. In Fig. 22, I have shown independent members 4^c, which may be secured to the leg by rivets 55. The other legs toward the front of the bench may have turned over top portions 37^b secured to the horizontal portions of the flange members 4^a by rivets 39^b. In each of these constructions, I provide cross bracing members or

backs 8^c with brackets 7^c, which are secured together and to the leg by means of bolts 42^c.

Figs. 24 and 25 show clearly the construction of the leg and the connection. The rivets 55 which secure the legs together may be provided with filler members 56.

It will be noted that in the several structures illustrated, each bench leg is substantially a single piece since the reinforcing foot plate is not necessarily essential, and that a complete bench support may consist of but six pieces, to wit: two legs, a bottom cross brace, two angle members, and a bracket. In some instances, as I have described and illustrated, I may use T-iron members at the upper ends of the legs instead of the pair of angle members, thereby reducing the number of parts of a complete bench support to five.

It will be understood, of course, that various modifications in the several connections will naturally suggest themselves to any one skilled in the art; hence I do not wish to be limited to the particular constructions illustrated in the drawings and described herewith.

As my application contains matter in common with an application filed April 29, 1916, Serial No. 94,452, it is to be treated as 85 a continuation of such earlier application in so far as the common subject-matter is concerned.

I claim:

1. A bench leg comprising a channel section having a central web with flanged sides substantially at right angles to the web, a supporting member horizontally disposed having a depending flange; said leg being slotted for the reception of the flange of 90 said supporting member and having its flanged sides inturned to underlie the horizontal portion of said supporting member, and means for rigidly securing said parts together.

2. The combination, in a metal bench support, of a pair of legs comprising channel sections, a supporting cross member in the upper ends of said legs comprising an angle section with horizontal and vertical flanges; 105 the upper ends of said legs being slotted to receive the vertical flanges of said supporting cross member and having inturned portions underlying the horizontal flanges thereof, and means for securing together the 110 legs and the horizontal support.

HOWARD T. HALLOWELL.
